(**) Term: **14 Years**

CLAIM

(21) Appl. No.: **29/151,097**

The ornamental design for portable wireless terminal equipment, as shown.

(22) Filed: **Dec. 5, 2001**

DESCRIPTION

(30) **Foreign Application Priority Data**

Jun. 6, 2001 (JP) 2001-016541

(51) **LOC (7) Cl.** **14-02**

(52) **U.S. Cl.** **D14/346**

(58) **Field of Search** D14/341-346;
D18/1, 2, 7; 235/145 A, 145 R; 341/22,
23; 345/156, 168, 169, 172, 173; 349/12;
361/680-686

(56) **References Cited**

FIG. 1 is a perspective view of the top, front and right side of a portable wireless terminal equipment showing our new design;
FIG. 2 is a top plan view thereof;
FIG. 3 is a bottom plan view thereof;
FIG. 4 is a front elevational view thereof;
FIG. 5 is a rear elevational view thereof;
FIG. 6 is a left side elevational view thereof; and,
FIG. 7 is a right side elevational view thereof.
